BINDING AND PIPING ATTACHMENT FOR
SEWING MACHINESWalter C. Greist and Carl G. Baehr, New Haven,
Conn., assignors to The Greist Manufacturing
Company, a corporation of Connecticut

Application April 9, 1936, Serial No. 73,544

1 Claim. (Cl. 112—137)

This invention relates to an improvement on the binding and piping attachments for sewing machines covered by U. S. Patents Nos. 1,853,412 and 1,853,413, and has for its object to provide an attachment capable of doing the work performed by the devices of the said patents in guiding a binder tape or strip and one or more piping tapes or strips to the needle of a sewing machine, in simultaneously attaching such tapes or strips to the edge of a piece of textile fabric.

10 This improved attachment, however, is of much simpler construction than the attachments of said patents and can be made at much less cost.

15 In the accompanying drawing Fig. 1 is a plan view of the improved attachment. Fig. 2 is a side view of the same looking from the right of Fig. 1. Fig. 3 is a section on line 3—3, Fig. 1, and Fig. 4 is a partial section on line 4—4, Fig. 2, looking down, Figs. 3 and 4 showing the parts greatly enlarged.

20 Referring to the drawing, 12 denotes a presser-foot having a shank 13 by which it may be attached to the presser-bar of a sewing machine, said presser-foot having a needle hole 14. Attached to the presser-foot 12, by a rivet 15, is a plate 16 to which is secured, preferably by soldering, a scroll 17. The scroll is constructed with a series of slots 18 of different heights or lengths for the purpose of accommodating binding tapes or strips of different widths, or for the purpose 25 of receiving a binder tape or strip and one or more wider piping tapes or strips, these piping tapes or strips being successively wider than each other when plural piping is to be done.

30 Beneath the head of the rivet 15 is a bowed spring 19 bearing on the plate 16 so that said plate is frictionally attached to the presser-foot 12 and may be adjusted laterally by the upwardly projecting lug 20, integral with said plate and which may be grasped by the thumb and finger of 35 the operator. By virtue of this adjustment the line of stitching, relative to the edge of the work to which the binding and piping strips or tapes are being attached, may be varied, as will be understood. To accommodate such adjustments 40 the needle-hole 21 in the plate 16 is in the form of an elongated slot.

45 The important novel feature of the invention is in the particular construction of the scroll 17. The right hand edges 24 of the in-turned parts 50

scroll being in close proximity to the inner concave face of the upwardly extending or vertical part of the scroll. One or both of these parts 22 is or are constructed with forward extensions 23, and the curved part of the upwardly extending or vertical portion of the scroll has a forward extension 25, all of which extensions run close up to and substantially in contact with the presser-foot 12, and thus reach near to the needle-hole 14 in said foot.

10 Owing to this construction of the scroll 17 the binding and piping tapes or strips passing through the scroll 17 will be securely pressed against the inner concave face of the scroll and will, in the operation of the invention, be securely guided and controlled in their passage from the delivering end of the scroll close up to the needle, thus accurately governing the stitching in its desired proximity to the edge of the binding strip, regardless of what width of binding is being used, even when attaching the narrowest folded binding strips or tapes to the edges of textile fabrics.

15 Although it may be advisable to construct both of the in-turned parts 22 with the extensions 23, it has been found, in practice, that the improved attachment will work satisfactorily or successfully with only the lower extension 25.

20 It will be understood that the work performed by the use of this attachment will be alike on both sides, which is desirable with some kinds of goods, as in finishing the edges of curtains, both 25 sides of which are more or less exposed.

We claim:

25 A sewing machine binding and piping attachment comprising a presser-foot having a needle-hole, a plate mounted on said presser-foot, a scroll secured to said plate and having a plurality of slots of different heights or lengths, the inner edges of the in-turned parts of the lobes of said scroll being in proximity to the inner concave 30 face of the vertical part of said scroll, and the forward end or ends of one or both of said in-turned parts being extended forward so as to be close up to and substantially in contact with said presser-foot and near the said needle-hole, and means permitting lateral adjustment of said plate 35 and the scroll attached thereto on said presser-foot.
